UNITED STATES PATENT OFFICE.

JOSEPH CURRY, OF RENTON, WASHINGTON.

SAFETY-BRAKE FOR ELEVATORS.

1,311,050.

Specification of Letters Patent. Patented July 22, 1919.

Application filed February 1, 1919. Serial No. 274,395.

To all whom it may concern:

Be it known that I, JOSEPH CURRY, a citizen of the United States, residing at Renton, in the county of King and State of Washington, have invented new and useful Improvements in Safety-Brakes for Elevators, of which the following is a specification.

This invention relates to improvements in safety brakes for elevators and has particular application to a brake which will operate automatically upon the parting of the hoisting or lifting cable to check the downward motion of the car.

In carrying out the present invention it is my purpose to provide an automatic brake of the class described which, upon the parting of the main cable, will automatically engage the guide rails or tracks to check the downward movement of the car, and which embodies comparatively few parts and these so arranged and correlated as to reduce the possibility of derangement to a minimum.

With the above recited objects in view and others of a similar nature, the invention consists in the construction, combination and arrangement of parts set forth in and falling within the scope of the appended claims.

In the accompanying drawings:—

Figure 1 is a fragmentary vertical sectional view through an elevator shaft with the car therein showing my invention applied.

Fig. 2 is a fragmentary horizontal sectional view through the same, part of my improved safety device being shown in section and other parts in plan.

Fig. 3 is a fragmentary perspective view of one of the operating levers.

Fig. 4 is a perspective view of one of the rail engaging members.

Referring now to the drawings in detail 1 designates an elevator shaft, while 2—2 indicates the vertical guide or track rails arranged within the shaft at opposite sides thereof and extending from the top to the bottom of the shaft. Within the shaft 1 is a car 3 capable of vertical movement within the shaft and secured to the opposite sides 50 of the car 2 are guide shoes 4 designed to engage the guide rails 2 to hold the car in proper position in its upward and downward movement within the shaft.

Extending across the top of the car 3 and 55 appropriately fast thereto are bars 5—5

spaced apart in parallelism and having the ends thereof projecting beyond the sides of the car or cage 3. The confronting faces of the bars 5—5 at the end portions thereof are preferably, although not necessarily thickened and formed with vertical grooves or channels 6 that receive the guide rail 2. Also formed in the confronting faces of the bars 5—5 at the end portions thereof are horizontal grooves or channels 7 that intersect the grooves 6 and open onto the end of the bar. In the present instance these grooves or channels 7 are dovetailed and slidably mounted within the respective grooves or channels 7 are clamping elements 8. In the present instance each clamping element 8 comprises a plate 9 that has its opposite side edges formed to fit into the corresponding dovetailed groove or channel 7, and a right angularly disposed jaw 10 integral with one end of the plate 9. The jaws 10 of the clamping devices at the corresponding ends of the bars 5 extend into the channels in the respective sides of the particular guide rail 2. Formed in each plate is an elongated opening 11. The openings 11 in corresponding plates 9 align with each other and arranged within such aligning openings are disks 12 that are mounted eccentrically upon a pivot bolt 13 that is mounted in grooves formed in the bars 5 as clearly shown in the drawings. Fixed upon the bolts 13 between the eccentrically mounted disks 12 are the outer ends of the levers 14. The inner ends of these 90 levers 14 project toward each other and terminate short of each other. Inter-connecting the inner ends of the levers 14 and pivotally connected thereto is a block 15 while encircling the block 15 is an inverted U-shaped yoke 16 that has its ends fastened to the bars 5—5 or to the top of the car or cage 3. Interposed between the upper members of the yoke 16 of the block 15 is an expansion spring 17 of suitable construction. The block 15 is connected with the hoisting cable 18 through the medium of a link 19 which, in the present case, extends through an opening 20 formed in the top of the yoke 16. The outer ends of the 105 levers 14 are formed with serrated cam heads 21 which, under the present conditions are designed to engage the inner sides of the guide rails 2.

In practice, as long as the hoisting cable 110

18 is intact, the ends of the levers 14 are elevated and the cam head 21 held out of engagement with the guide rail, incident to the hoisting cable counter-acting the spring 5 17. The jaws 10 of the clamping devices are also held out of engagement with the guide rail as long as the hoisting cable is intact, owing to the fact that the disks 12 in the elongated slots 11 hold the clamping 10 devices in inactive position.

When, however, the hoisting cable parts, the spring reacts and lowers the inner ends of the levers 14. In the downward movement of the inner extremities of the levers 15 14 the cam heads 21 engage the guide rails 2. In the movement of the cam heads to engage the guide rails the pivot bolts 13 are rocked and the eccentrically mounted disks 12 slide the plates 9 inwardly with the effect to engage the jaws 10 with the guide 20 rails. Thus the jaws 10 of the clamping devices and the cam heads 21 coöperate to produce a clamping action on the guide rails so as to hold the car or cage 3 against downward movement in the shaft. 25

I claim:

1. In a safety brake for elevators, the combination with vertical guide rails, of horizontally disposed bars secured to the top 30 of the car and spaced apart, the opposite ends of said bars being relatively thick and provided with intersecting vertical and horizontal grooves, a clamping element slidably mounted in the horizontal grooves at each end of the bars, a right angularly disposed jaw on each element arranged within the vertical groove and normally spaced from said guide rails, levers pivoted between the 35

bars, a connection between the adjacent ends of said levers and the hoisting cable, whereby said levers are normally elevated, means providing a connection between the said levers and clamping elements, to move the latter into engagement with the guide rails when the levers are lowered, and means for 40 lowering said levers upon the braking of the 45 cable.

2. In a safety brake for elevators, the combination with vertical guide rails, of horizontally disposed bars secured to the top 50 of the car and spaced apart, the opposite ends of said bars being relatively thick and provided with intersecting vertical and horizontal grooves, a clamping element slidably mounted in the horizontal groove at each end of said bars, a right angularly disposed jaw on each element arranged within the vertical groove and normally spaced from the guide rails, of levers pivoted between said bars, a connection between the adjacent ends of said levers and hoisting cable, whereby said levers are normally held elevated, each of said clamping elements having an elongated slot, eccentrically mounted 55 disks carried by the opposite or outer ends of said levers and operating within the slot of said clamping element, to move the latter into engagement with the guide rails upon lowering of said levers incident to the braking of the cable, and the outer ends of 60 said levers being provided with teeth to engage the guide rails simultaneously with said clamping element.

In testimony whereof I affix my signature.

JOSEPH CURRY.
